ELECTROMAGNETIC CONTACTOR

William C. Stevens, Milwaukee, Wis., assignor to
 Cutler-Hammer, Inc., Milwaukee, Wis., a corporation of Delaware

Application August 28, 1937, Serial No. 161,364

10 Claims. (Cl. 175—338)

This invention relates to improvements in electromagnetic contactors. Certain features of the invention are particularly applicable to alternating current contactors.

5 An object of the invention is to generally improve and simplify the details of construction and assembly of the parts of electromagnetic contactors.

Another object is to provide a novel form of 10 combined shading coil and coil clamp for alternating current contactors.

Another object is to provide for ready removal of the combined shading coil and coil clamp, to facilitate replacement thereof and to permit 15 inspection of other parts of the contactor.

Another object is to provide a novel form of stop for the armature of the contactor.

Another object is to provide novel means for 20 adjustably mounting the armature stop.

Another object is to provide a one-piece combined shading coil, coil clamp and armature stop, together with novel means for removably 25 mounting the same.

Another object is to provide novel means for 30 resiliently and frictionally mounting the operating winding with respect to the magnet core.

Another object is to provide a novel form of 35 bridging contactor and novel means for releasably supporting the same in assembled relation to the armature.

Other objects and advantages of the invention 40 will hereinafter appear.

The accompanying drawing illustrates certain 45 embodiments of the invention which will now be described, it being understood that the embodiments illustrated are susceptible of modification in respect of certain details of construction thereof without departing from the scope of the appended claims.

40 In the drawing,

Figure 1 is a plan view of an alternating current contactor constructed in accordance with 45 my invention.

Fig. 2 is a sectional view, substantially on the line 2—2 of Fig. 1.

Fig. 3 is a view similar to Fig. 1, but with the armature and the bridging contactor removed, to show the arrangement of the combined shading coil and clamp for the operating coil or winding of the contactor.

Fig. 4 is a detail perspective view of the combined shading coil and coil clamp member.

Fig. 5 is a detail perspective view of one of the 55 reflexed resilient members to be frictionally inter-

posed between the laminated core arm and the operating winding associated with the latter.

Fig. 6 is a detail perspective view of the adjustable armature stop member which may be employed.

Fig. 7 is a fragmentary sectional view similar to Fig. 2, but showing a modification wherein the armature stop element is formed integrally with the combined shading coil and coil clamp member, and

Fig. 8 is a detail perspective view of the combined shading coil, coil clamp and armature stop member illustrated in Fig. 7.

Referring first to Figs. 1 to 5, inclusive, the numeral 10 designates a base or plate formed of 15 suitable insulating material, such as a laminated fiber board impregnated with the phenol formaldehyde condensation product sold commercially under the trade name of "Bakelite." Plate 10 may be provided with two or more suitably positioned openings (not shown) to facilitate attachment thereof to a panel or the like.

Secured to plate 10 as by means of a pair of screws 11 is a magnet core member 12 of substantially U-shape,—said member having a relatively short arm 13 and a relatively long arm 14. Arm 14 is beveled, as shown in Fig. 2, to provide a knife-edge 15. Member 12 is preferably composed of a metal strip bent to the form illustrated.

Loosely pivoted upon the relatively long arm 30 14 and adapted to bear against the knife edge 15 is an armature 16, which is preferably cut to the desired length from a metal strip. To assist in pivoting armature 16 to arm 14 I preferably spot weld or otherwise rigidly attach to the 35 former a bracket 17 having a portion 18 which overlies a portion of the inner surface of arm 14 and a pair of downwardly extending lugs 19 and 20 which respectively engage opposite edges of said arm.

40 Armature 16 is provided adjacent its lower end with a drilled recess or cavity 21 which is adapted to receive the specially formed hooked end 22 of a coiled tension spring 23. The other end of spring 23 is provided with a hooked end 45 24 of usual form, which is adapted to penetrate an opening 25 and notch 26 in portion 27 of a bracket 28 which is spot welded or otherwise rigidly secured to the lower surface of arm 14, as shown in Figs. 2 and 3. Spring 23 thus acts to 50 bias armature 16 to its retracted position,—suitable means being provided to limit the degree of retracting movement of the armature, as herein-after described.

Armature 16 is provided with a drilled open- 55

ing to receive the reduced shank 29 of a pin 30, and a countersink or recess to accommodate the upset end of said shank, as shown at 31, in a relation flush with or within the inner surface 5 of said armature. Armature 16 is provided with a second drilled opening, alined with the opening aforementioned, to accommodate the shank of a rivet 32. Telescoped onto rivet 32 between the head 33 of the latter and the outer surface of 10 armature 16 are a pair of metal washers 34 and 35 and a tube or ferrule 36,—a coiled compression spring 37 bearing at one end against washer 34 and surrounding washer 35 to be centered by the latter.

15 Carried by armature 16 is a bridging contactor 38 of substantially T-shape,—the head of said contactor having an open slot 39 which accommodates with a sliding fit the aforementioned ferrule 36 surrounding rivet 32. That portion of 20 slot 39 which surrounds ferrule 36 is provided with an upstanding flange 40 (Fig. 2) which is accommodated by the inner end of spring 37, whereby contactor 38 is yieldably biased toward, or into a given relationship to, the armature 16.

25 The shank portion of contactor 38 is provided with a circular opening 41 to loosely accommodate the aforementioned rivet 30,—an upstanding flange 42 surrounding said opening for cooperation with said rivet to assist in retaining 30 said contactor in proper relationship to armature 16. As shown in Fig. 2 the shank of rivet 32 is upset, as indicated at 43, whereby the same is mounted in a rigid position with respect to armature 16.

35 Rigidly secured to core member 12 between arms 13 and 14 is a laminated core arm 44,—the laminations of which are rigidly attached or clamped to each other, as by means of a rivet 45. The means for securing arm 44 to core 12 preferably 40 comprises a pair of flat-head screws (not shown) countersunk into the outer surface of member 12, and taking into correspondingly located tapped openings provided in the inner end of arm 44. The outer end of arm 44 is preferably 45 located in or ground to a plane flush with the outer end of long arm 14,—and said end of arm 44 is provided with a kerf or groove 46 to accommodate the shading coil hereinafter described. I preferably interpose between the inner 50 end of arm 44 and core member 12 an insulating plate or spacer 47.

Adapted to surround arm 44 is a preformed operating winding or coil 48,—the wiring terminals of which extend from opposite sides 55 thereof as shown at 49 and 50 in Figs. 1 and 3. Winding 48 is frictionally but removably retained in proper position with respect to arm 44 as by means of a pair of reflexed resilient metal members 51 arranged on opposite sides of arm 44 (Fig. 3), one of said members being shown in detail in Fig. 5. Members 51 are positioned with the bent portions thereof adjacent the outer end of arm 44, and winding 48 is then pressed inwardly to the position thereof shown in Fig. 2.

60 Superimposed upon the upper surface of short arm 13 (Fig. 2) is the horizontal portion 52 of a combined shading coil for the outer face of arm 44 and clamp for winding 48. Said combined member is preferably of inverted L-shape, and the 65 vertical portion 53 thereof is adapted to overlap the outer end of arm 44,—said vertical portion having an opening 54 to accommodate a portion of the pole face of arm 44,—the part 55 of said vertical portion being adapted to fit within the 70 aforementioned groove 46, whereby a shading 75

coil is provided for the pole face of said arm 44. As shown, the vertical portion 53 overlaps a portion of winding 48, whereby endwise displacement of the latter from arm 44 is positively prevented.

5 Superimposed upon horizontal portion 52 is a stop 56 for the armature 16. Stop 56 preferably comprises a flat punched metal plate having a rectangular opening 57 (Fig. 2) which is adapted to accommodate the reduced upper end or extension 58 of armature 16. The outer wall 59 of opening 57 is adapted for engagement by the outer surface of extension 58 of armature 16 to limit the degree of retracting movement of the latter. If it is desired to increase the air gap 15 between armature 16 and the pole face of arm 44 this may be accomplished by filing or grinding away to the desired extent the wall 59 of opening 57.

As shown, the short arm 13 (Fig. 2) of core 20 member 12 is provided with a pair of tapped openings to receive the shanks of a pair of screws 60,—horizontal portion 52 and stop plate 56 having openings to provide clearance for said screw shanks. Interposed between the heads of said 25 screws and plate 56 are suitable lock washers 61 to prevent accidental loosening thereof. By this arrangement horizontal portion 52 and plate 56 may be rigidly secured to core arm 13. By reason of the clearance between the walls of the openings in plate 56 and the shanks of screws 60 a slight degree of adjustment of the position of wall 59 of opening 57 in said plate may be effected prior to tightening of said screws.

As shown in the modified form of armature stop 35 plate 56^a of Fig. 6, a greater degree of adjustment of the position of wall 59^a of opening 57^a may be effected by providing elongated or elliptical clearance openings for the shanks of securing screws 60, as indicated at 62 and 63. 40 Such an arrangement obviates the necessity for filing or grinding away the wall 59^a of the plate opening to provide the desired air gap between armature 16 and the pole face of arm 44. The arrangement illustrated in Fig. 6 likewise provides 45 for an adjustment to decrease the amount of the air gap when desired. It will be understood, of course, that plate 56^a may be substituted for the plate 56 of Figs. 1 and 2 without requiring any changes in the other elements of the contactor.

As best illustrated in Fig. 1, contactor 38 has 50 attached to the inner surface of the opposite ends thereof a pair of contact tips, shown in dotted lines at 64 and 65. Said tips are preferably of substantially cylindrical form,—the contacting portions preferably being composed of coin silver with a backing or layer of nickel silver alloy, whereby the same may be rigidly attached to contactor 38 by a welding operation.

The stationary contacts likewise preferably 55 comprise plates 66 and 67 to which tips 68 and 69 of the aforementioned character are rigidly attached, as by welding. Plates 66 and 67 are rigidly secured by screws 70 and 71 to the 60 angularly arranged forward end portions of a pair of brackets 72 and 73,—said brackets being of approximately U-shape, as best illustrated in Fig. 2. The rear end portions 74 and 75 of brackets 72 and 73 are attached to insulating 65 plate 10 as by means of pairs of screws, the pair of attaching screws 76 and 77 for portion 76 being shown in Fig. 2, and one screw 78 of the pair associated with portion 75 being shown in Figs. 1 and 3. The shanks of screws 77 and 78 70

are made relatively long, whereby each is adapted to receive a clamping nut 79 (Fig. 2), a cup washer 80, a wire clamping nut 81, and a slotted nut 82 which may act as a lock for nut 81.

5 In Figs. 7 and 8 I have shown a modified form of the device wherein a single metal member 83 is provided with a vertical portion 84 adapted to clamp or retain the operating winding 48 (Fig. 7) in assembled relation to the laminated core 10 arm 44, arm 84 having an opening 85 formed therein to provide a shading coil for the grooved pole face of core arm 44; an integral part 86 being sheared and bent outwardly therefrom to lie substantially in the plane of the horizontal 15 portion 87. Part 86 has an opening 88 formed therein to receive and to limit retractive movement of armature 16. As shown in Fig. 7, the screws 61^a for attaching horizontal portion 87 of member 83 to the relatively short core arm 13 20 are slightly shorter than the screws 61 of Fig. 2. The other elements of the device of Fig. 7 are like the corresponding parts aforescribed and have been given like numerals of reference.

In practice I prefer to form the bridging contactor 38 of phosphor bronze. The combined shading coil and coil clamp member 53 and the armature stop plates 56 and 56^a, in Figs. 1 to 5, are preferably formed of a suitable non-magnetic material, such as brass. Similarly, the one-piece combined shading coil, coil lamp and armature stop member 83 of Figs. 7 and 8 is preferably formed of brass. The magnetic core and armature elements of the contactor are, of course, preferably formed of steel.

35 What I claim as new and desire to secure by Letters Patent is:

1. In an electromagnetic contactor, in combination, a magnet core comprising three parallel arms, an operating winding surrounding the intermediate arm and spaced inwardly from the 40 free end of the latter, a one-piece substantially L-shaped sheet metal member having one portion attached to an outer arm of said core and an integral loop-shaped portion overlapping the free 45 end of said core arm first mentioned, said free end having a groove formed in the forward face thereof and said loop-shaped portion having an integral part formed to fit within said groove whereby a shading coil is provided, and said loop-shaped portion also acting to positively prevent 50 displacement of said operating winding from said magnet core.

2. In combination, a magnet core of substantially E-form, a magnetizing coil surrounding the 55 intermediate arm of said core, said intermediate arm being of laminated form and having a groove formed in the pole-face thereof, a one-piece metal strip bent to substantially L-shape, one arm of said strip being secured to an end arm of 60 said core and the other arm of said strip being arranged in overlapping relation to the pole face of said intermediate arm of the core, said overlapping arm of the strip having an opening formed therein to accommodate a portion of said 65 pole face, an integral portion of said last mentioned arm being adapted to fit within the groove in said pole-face whereby a shading coil is provided for the latter, said last mentioned arm also acting to positively prevent displacement of said 70 magnetizing coil from said intermediate arm of the core.

3. In an alternating current contactor, in combination, a magnet core having a plurality of spaced substantially parallel arms, a magnetizing 75 coil positioned upon one of said arms, a combined

shading coil and coil clamp member, said member comprising a sheet metal strip bent to substantially L-shape, the horizontal portion of said member having a plurality of openings formed therein, a plurality of fastening elements penetrating said openings and engaged with another of said core arms to rigidly secure said parts in assembled relation, said first mentioned core arm having a groove formed in the pole face thereof, the vertical portion of said member having an opening formed therein adjacent to the free end thereof, said last mentioned opening being surrounded by the metal of said strip and the same being adapted to accommodate a portion of the grooved pole face aforementioned, whereby a shading coil is provided, and said vertical portion also acting to retain said magnetizing coil in position upon said core arm first mentioned.

4. As an article of manufacture, a combined shading coil, coil clamp and armature stop member for alternating current magnets, said member comprising a metal strip bent to provide a horizontal portion and a vertical portion, said horizontal portion being formed to provide for rigid attachment thereof to one arm of a magnet 25 core, said vertical portion having an opening formed therein adjacent the lower end thereof to accommodate a portion of the grooved pole face of another arm of the magnet core, whereby a shading coil is provided, said vertical portion also 30 acting to clamp a suitable magnetizing winding in assembled relation to said last mentioned arm of the core, said vertical portion having an integral portion of substantially loop-shape sheared and bent with respect thereto to lie substantially 35 within the plane of said horizontal portion, and said portion of loop-shape being adapted to accommodate therewithin a portion of an armature, to thereby positively limit movement of the armature in one direction.

5. In combination, a combined shading coil and coil clamp member for alternating current magnets, said member comprising a metal strip bent to provide a horizontal portion and a vertical portion, said horizontal portion being formed to 45 provide for rigid attachment thereof to one arm of a magnet core, said vertical portion having an opening formed therein adjacent the lower end thereof and surrounded by the metal of said strip to accommodate a portion of the grooved 50 pole face of another arm of the magnet core, whereby a shading coil is provided, said vertical portion also acting to clamp a suitable magnetizing winding in assembled relation to said last mentioned arm of the core, and an element arranged in fixed relation to said combined member 55 aforementioned, said element having an opening formed therein, one wall of said opening being engageable by an armature of suitable form to positively limit movement of the latter when released.

6. In combination, a combined shading coil and coil clamp member for alternating current magnets, said member comprising a metal strip bent to provide a horizontal portion and a vertical portion, said horizontal portion being adapted to be superimposed upon one arm of a magnet core of suitable form, an armature stop comprising a flat member superimposed upon said horizontal portion, a pair of securing screws, said flat 65 member and said horizontal portion having openings to provide clearance for the shanks of said screws, which take into tapped openings provided in said core arm whereby said flat member 70 and said horizontal portion may be clamped in 75

- position, the aforementioned openings in said flat member being of elongated form to provide for a substantial degree of adjustment of said flat member relatively to said core arm, said flat member having a relatively large opening formed in the free end thereof to accommodate a portion of the magnet armature, the outer wall of said last mentioned opening being adapted to positively limit the degree of releasing movement of the armature, the aforementioned vertical portion of said combined element having an opening formed therein adjacent the lower end thereof and surrounded by the metal of said strip to accommodate a portion of the grooved pole face of another arm of the magnet core, whereby a shading coil is provided, and said vertical portion also acting to clamp a suitable magnetizing winding in assembled relation to said last mentioned arm of the core.
5. In an alternating current contactor, in combination, a magnet core comprising a metal strip bent to approximately U-shape to provide a relatively long arm and a relatively short arm, an armature pivotally supported by said relatively long arm, said core having attached thereto an intermediate arm of a length corresponding to said relatively long arm, said intermediate arm being of laminated construction and having a groove formed in the forward face thereof, an operating winding surrounding said intermediate arm, a non-magnetic member of inverted L-shape having a portion attached to said relatively short arm and another portion adapted to overlap said forward face of the intermediate arm, said last mentioned portion having an opening formed therein to accommodate a portion of said forward face, an integral part of the surrounding wall of said opening being adapted to fit within said groove to provide a shading coil for said forward face, and said last mentioned portion being adapted to overlap a portion of said operating winding, whereby the latter is positively restrained against displacement from said intermediate arm.
6. In an alternating current contactor, in combination, a magnet core comprising a metal strip bent to approximately U-shape to provide a relatively long arm and a relatively short arm, an armature pivotally supported by said relatively long arm, said core having attached thereto an intermediate arm of a length corresponding to said relatively long arm, said intermediate arm being of laminated construction and having a groove formed in the forward face thereof, an operating winding surrounding said intermediate arm, a plurality of reflexed resilient metal members interposed between said intermediate arm and the adjacent inner surfaces of said winding, whereby the latter is frictionally held in position, a member of inverted L-shape having a portion attached to said relatively short arm and another portion adapted to overlap said forward
7. In an alternating current contactor, in combination, a magnet core having a laminated arm of substantially rectangular form in cross section, a pair of reflexed resilient metal strip members of substantially V-shape respectively positioned on opposite sides of said arm, the bent portions of said members being positioned adjacent the forward end of said arm, an operating winding telescoped onto said arm and engaged with the outer arms of said members to be frictionally retained in position by the latter, and a one-piece punched and stamped sheet metal shading coil member removably secured to another arm of said core and having an integral loop-shaped portion overlapping a portion of the forward end of said laminated arm, said loop-shaped portion also overlapping the forward end of said winding, whereby the latter is positively restrained against displacement from said laminated arm.
8. In an alternating current contactor, in combination, a magnet core comprising a metal strip bent to substantially U-shape to provide a relatively short arm and a relatively long arm, an arm of laminated construction rigidly secured to said core between the arms aforementioned, said laminated arm having a groove formed in the forward face thereof, an armature pivotally supported by said relatively long arm, said armature being spring biased to retracted position, an operating winding carried by said laminated arm, a one-piece inverted L-shaped sheet metal member having a horizontal portion superimposed upon said relatively short arm and a vertical portion formed for cooperation with the grooved face of said laminated arm to provide a shading coil, said vertical portion overlapping a portion of said winding to retain the latter in position, a separate sheet metal stop member having a portion superimposed upon said horizontal portion, said stop member and said horizontal portion having openings to accommodate the shanks of clamping screws which take into tapped openings in said relatively short arm, the openings in said stop member being elongated to provide for adjustment of the latter relatively to said core, said stop member having an opening formed in the free end portion thereof, and said armature having a portion movable within said opening to positively limit the degree of retracting movement of said armature.

WILLIAM C. STEVENS.
